ROTARY LOOP-TAKER FOR SEWING MACHINES

James E. Wertz, Ware Shoals, S. C., assignor to
The Singer Manufacturing Company, Elizabeth,
N. J., a corporation of New Jersey

Application October 7, 1941, Serial No. 413,915

16 Claims. (Cl. 112—228)

This invention relates to sewing machine loop-takers and is particularly applicable to rotary loop-takers having a cup-shaped body in which is journaled a thread-carrier restrained against rotation with the loop-taker.

Woven sheet materials of various kinds contain a filling of extraneous or foreign matter; a substantial percentage of which matter becomes dislodged by the needle and the feeding mechanism of a sewing machine when stitching said materials. The dislodged extraneous matter referred to may adhere to the inner face of the loop-taker, and to the outer face of the thread-carrier proximate to said inner face of the loop-taker, in sufficient quantity to interfere with stitch-formation and to result in the skipping of stitches. This condition has required frequent washing of the loop-taker and its thread-carrier to clear them of the collected extraneous matter, thereby resulting in loss of production by the sewing machine.

The present invention has for its primary object to reduce to a minimum, during sewing operations, the accumulation of sheet-material extraneous matter upon the thread-carrier associated with a rotary loop-taker of a sewing machine, and to correspondingly minimize the skipping of stitches. Other and more specific objects of the invention will be apparent from the following description and claims.

The invention consists in the association with a sewing machine loop-taker of a wiper or deflector device, a preferred embodiment of which is hereinafter described in connection with the accompanying drawing, in which:

Fig. 1 is a top plan view of a horizontal-axis rotary loop-taker containing the wiper device improvement, a fragment of the thread-carrier rotation-restraining finger being also shown in top plan. Fig. 2 is a front end elevation of the loop-taker in a position slightly advanced angularly beyond that shown in Fig. 1. Fig. 3 represents a cross-section of the proximate walls of the loop-taker and its thread-carrier in the region of the wiper device, the section being taken substantially on the line 3—3 of Fig. 2. Fig. 4 is a rear side elevation of the loop-taker in substantially the position thereof illustrated in Fig. 2, and with the bobbin-thread pull-off flange partly broken away. Fig. 5 is a front end elevation of a fragment of the loop-taker as shown in Fig. 2, with the wiper element omitted. Fig. 6 represents a perspective view of the loop-taker, with the thread-carrier and its retaining gib omitted. Fig.

7 represents a perspective view of the thread-carrier of the loop-taker.

As illustrated in the drawing, the present improvement has been embodied in a horizontal-axis loop-taker constructed substantially as disclosed in the U. S. patent to C. A. Kessler, No. 2,085,699, June 29, 1937.

Referring to the drawing, the loop-taker has a generally cup-shaped body member, including a cylindrical side wall 10, and a bottom wall 11 which has a hub 12 adapted to be secured by screws 13 upon a horizontally disposed rotary actuating shaft (not shown). The cylindrical side wall 10 of the loop-taker is partly cut away to provide at its outer edge a needle-thread loop seizing beak 14. The loop-seizing beak 14 is opposed to and spaced slightly from a loop-discharging tail or spur 15 provided upon a segmental gib 16; said gib 16 being detachably secured by screws 17 upon the cylindrical side wall 10 of the loop-taker.

Detachably secured by screws 18 upon and overlying a portion of the cylindrical side wall 10 of the loop-taker body is a segmental sheet-metal plate 19. The tapered advance end 19' of the segmental plate 19 is disposed to extend partly across the gap between the beak 14 and the tail 15 of the loop-taker, said tapered end 19' of the plate being as usual complementary to the beak 14 in directing the limbs of the seized needle-thread loops. One side edge 20 of the segmental plate 19 is curved to extend outwardly beyond the rim of the loop-taker side wall 10, thereby to function as a pull-off flange for the interlocking or bobbin-thread. The thread pull-off end portion or heel of the segmental-plate 19 is provided with the usual needle-clearance notch 21, said notch being disposed substantially diametrically opposite to the beak 14.

40 The side wall 10 of the loop-taker body is cut away circumferentially to provide an internal raceway 22, said raceway being in part completed by a side flange 23 of the segmental and detachable gib 16. Journaled in the raceway 22, and thereby having a bearing-support in the loop-taker body, is a bearing-rib 24 formed upon and extending circumferentially of a generally cylindrical side wall 25 of a thread-carrier member 26. The bearing-rib 24 is interrupted to provide the usual needle-thread clearance gap between the shoulder-defining opposed ends 27 and 28 of the bearing-rib. Disposed within the thread-carrier 26 is a bobbin-case 29 containing a bobbin (not shown) of interlocking thread about which needle-thread loops are cast by the loop-

taker in the formation of lock-stitches. The bobbin-case 29 is releasably secured by a latch 30 to a central post 31 of the thread-carrier 26.

The outer rim of the thread-carrier 26 has formed thereupon a segmental flange 32, said flange being shouldered at the upper portion thereof to provide a stop-notch 33 in the outer face of said flange 32. The stop-notch 33 of the thread-carrier is adapted to be loosely entered by a stop-lug 34 extending from a stationary stop-finger 35. Consequently, the thread-carrier 26 is as usual restrained against rotation with the loop-taker body-member 10, 11, 12. The cylindrical side wall 25 of the thread-carrier 26 is provided with the usual needle-clearance slot 36 disposed directly adjacent the stop-notch 33 of the thread-carrier, the segmental flange 32 being partly cut away at the inner side thereof to form said slot 36.

In the operation of a lock-stitch sewing machine containing the loop-taker hereinbefore described in general terms, the usual sewing machine needle (not shown) in its descent enters the thread-carrier slot 36 and, while in said slot, rises sufficiently to present a loop of needle-thread for seizure by the beak 14 of the loop-taker. Should the thread-carrier slot 36 and the adjacent face of the thread-carrier be permitted to become clogged by foreign matter such as becomes dislodged during the stitching operation from heavily filled sheet-materials, the needle will fail in its function of presenting a thread-loop to the loop-taker beak 14, thereby resulting in the skipping of stitches.

In order to provide a maximum of bobbin-thread capacity for the thread-carrier 26 in a given size of loop-taker, the cylindrical side wall 25 of the thread-carrier is disposed in close proximity to the inner face of the cylindrical side wall 10 of the loop-taker body. However, it is essential to provide sufficient space to afford thread clearance between the inner face of the loop-taker wall 10 and the outer face of the thread-carrier wall 25, inasmuch as it is necessary to pass the needle-thread between said walls and through the gap between the shoulders 27 and 28 of the thread-carrier bearing-rib 24. It is therefore undesirable to permit clogging of the space between the proximate faces of the loop-taker wall 10 and the thread-carrier wall 25 by the adherence to said faces of foreign matter dislodged from sheet materials being stitched. As hereinbefore mentioned, it has been the prior practice to wash the loop-taker to remove therefrom collected foreign matter interfering with proper stitch-formation, and this has of course resulted in loss of production by the sewing machine.

In accordance with the present invention, the loop-taker is provided with means preventing, or at least reducing to a negligible minimum, the lodging of extraneous foreign matter upon the outer face of the thread-carrier wall 25 in an area thereof displaced axially from the bearing-rib 24 and in the needle-slot 36 of the thread-carrier. To this end, the side wall 10 of the loop-taker is provided with a transverse slot 37 extending from the outer rim of said side wall substantially to the raceway 22. The slot 37 is disposed substantially diametrically opposite to the beak 14 of the loop-taker and radially within the heel portion of the segmental-plate 19 at a point closely adjacent the needle-clearance notch 21 therein. The outer face of the wall 10 of the loop-taker at one

side of the slot 37 is partly cut away to form a depression 38 in said outer face.

Disposed in the depression 38 of the loop-taker wall 10, and clamped against said wall by the 5 detachable plate 19, are the overlapped ends of a flatwise doubled strip 39 of suitable flexible wiper material, preferably of leather. The overlapped plies of the flexible strip 39 are passed through the slot 37, and extend from said slot 10 generally circumferentially of the thread-carrier between the proximate faces of the wall 10 of the loop-taker and the wall 25 of the thread-carrier. The plies of the leather strip 39 naturally tend to spring apart at the doubled free 15 end of said strip, thereby forming a resilient wiper-element for the outer face of the thread-carrier wall 25 in the area of said wall displaced axially from the bearing-rib 24. The doubled free end of the wiper-element 39 underlies a 20 portion of the needle-clearance notch 21, said element widthwise extending partly across said notch so as to pass over a substantial width of the needle-clearance slot 36 of the thread-carrier during rotation of the loop-taker. The wiper-element 25 39 thereby functions constantly to prevent adherence of foreign matter to the outer face of the thread-carrier, adjacent the journal bearing of said thread-carrier, and to reduce to a negligible minimum the lodgment of said foreign matter in the needle-clearance slot 36 of the thread-carrier. The wiper-element also functions to baffle the lodgment of foreign matter upon the inner face of the loop-taker wall 10.

The inner side edges of the doubled wiper-element 39 are preferably disposed in sliding engagement with the outer side face of the thread-carrier bearing-rib 24, thereby tending to steady the thread-carrier 26 against canting responsive to a pull of the stitching threads.

40 Being located substantially diametrically opposite to the loop-taker beak 14, the wiper-element 39 passes over the needle-thread, extending through the bearing-rib gap of the thread-carrier, at approximately the time of maximum 45 expansion of the needle-thread loop by the loop-taker. The wiper-element thereby does not interfere with the expansion of the needle-thread loop by the loop-taker, and said wiper-element passes across the needle-thread at a time when 50 the tautness of said thread lends itself to non-interference by the wiper with the handling of the thread.

Having thus set forth the nature of the invention what I claim herein is:

55 1. In a sewing machine loop-taker including a member having a cylindrical body, and a thread-carrier member having a bearing support in said cylindrical body, one of said members being rotatable relatively to the other member, the improvement which consists in the provision of a wiper-element carried by one of said members and disposed in wiping relation to the proximate face of the other of said members in an area axially displaced from said bearing support.

2. In a rotary loop-taker for sewing machines, in combination, a loop-taker body-member having a cylindrical side-wall provided with a needle-thread-loop seizing beak and an internal raceway, a thread-carrier member having a bearing-rib journaled in said raceway, said thread-carrier member having a generally cylindrical side wall portion adjacent said bearing-rib proximate to but spaced from the side wall of said loop-taker body-member, and means disposed between said walls at one side of said bearing-rib and

rendered effective upon rotation of said members relative to each other for maintaining one of the proximate faces of said walls adjacent said bearing-rib and raceway substantially free from deposit thereupon of extraneous matter deleterious to stitch-formation.

3. A rotary loop-taker for sewing machines, including a body-member having a cylindrical side wall provided with a needle-thread-loop seizing beak and with an internal raceway, a thread-carrier member having a bearing-rib journaled in said raceway and having a generally cylindrical side wall portion adjacent said bearing-rib proximate to but spaced from the side wall of said loop-taker body-member, and means extending from one of said walls toward the proximate face of the other of said walls adjacent said bearing-rib and rendered effective upon rotation of said members relative to each other for maintaining said face substantially free from deposit thereupon of extraneous matter deleterious to stitch-formation.

4. A rotary loop-taker for sewing machines, including a body-member having a cylindrical side wall provided with a needle-thread-loop seizing beak and with an internal raceway, a thread-carrier member having a bearing-rib journaled in said raceway, said thread-carrier member having a generally cylindrical side wall portion adjacent said bearing-rib proximate to but spaced from the side wall of the loop-taker body-member, and a wiper-element disposed entirely at one side of said bearing-rib and extending from the inner face of the loop-taker body member toward the proximate face of said thread-carrier member.

5. A rotary loop-taker for sewing machines, including a loop-taker body member having a cylindrical side wall provided with a needle-thread-loop seizing beak, a thread-carrier member disposed within said loop-taker body member and having a generally cylindrical side wall portion proximate to but spaced from the side wall of said body-member, one of said members having a raceway and the other of said members having a bearing-rib journaled in said raceway, and a wiper-element carried by one of said members and disposed between the proximate faces of said side walls adjacent said bearing-rib and raceway.

6. A sewing machine loop-taker having a cylindrical side wall provided with a thread-loop seizing beak and with an internal raceway, a thread-carrier having a bearing-rib journaled in said loop-taker and having a generally cylindrical side-wall adjacent said bearing-rib proximate to but spaced from said side wall of the loop-taker, and a wiper-element disposed entirely at one side of said bearing-rib between the proximate faces of said side-walls substantially diametrically opposite to said beak of the loop-taker, said wiper-element being carried by said loop-taker for rotation therewith.

7. A rotary loop-taker for sewing machines, including a body-member having a cylindrical side wall provided with a needle-thread-loop seizing beak and with an internal raceway, a thread-carrier member having a bearing-rib journaled in said raceway, said thread-carrier member having a generally cylindrical side wall portion adjacent said bearing-rib proximate to but spaced from the side wall of said loop-taker body-member, and a flexible wiper-element extending from one of said walls adjacent said

bearing rib and raceway toward the proximate face of the other of said walls.

8. A rotary loop-taker for sewing machines, including a body-member having a cylindrical side wall provided with a needle-thread-loop seizing beak and with an internal raceway, a thread-carrier member having a bearing rib journaled in said raceway, said thread-carrier member having a generally cylindrical side wall portion displaced axially from said bearing rib and proximate to but spaced from the side wall of the loop-taker body-member, and a flexible wiper-element carried by said body-member of the loop-taker at one side of said raceway and extending from the inner face of said body-member toward the proximate face of said side wall portion of the thread-carrier member.

9. A loop-taker for sewing machines, including a rotary cup-shaped body-member having a cylindrical side wall provided with a needle-thread-loop seizing beak, a thread-carrier member journaled in said body-member of the loop-taker, said thread-carrier member having a generally cylindrical side wall portion proximate to but spaced from the side wall of said loop-taker body member, and a flexible wiper-element having one end thereof extending from the inner face of said side wall in a direction oppositely to said beak, said wiper-element having its opposite free end disposed substantially in engagement with the outer face of said side wall of the thread-carrier member.

10. A loop-taker for sewing machines, including a rotary cup-shaped body-member having a cylindrical side wall provided with a needle-thread-loop seizing beak, a thread-carrier member journaled in said body-member of the loop-taker, said thread-carrier member having a generally cylindrical side wall portion proximate to but spaced from the side wall of said loop-taker body member, and a wiper-element extending from one of said walls toward the proximate face of the other of said walls, said wiper-element comprising a doubled strip of flexible material having the doubled end thereof disposed substantially in engagement with said proximate face.

11. A loop-taker for sewing machines, including a rotary cup-shaped body-member having a cylindrical side wall provided with a needle-thread-loop seizing beak, a thread-carrier member journaled in said body-member of the loop-taker, said thread-carrier member having a generally cylindrical side wall portion proximate to the side wall of said loop-taker body-member, and a flexible wiper-element disposed between said walls, said wiper-element comprising a doubled strip of flexible material having the overlapped ends thereof attached to said side wall of the loop-taker and having the doubled end portion thereof disposed substantially in engagement with the outer face of the side wall of said thread-carrier.

12. A loop-taker for sewing machines, including a rotary cup-shaped body-member having a cylindrical side wall provided with a needle-thread-loop seizing beak, a thread-carrier member journaled in said body-member of the loop-taker, said thread-carrier member having a generally cylindrical side wall portion proximate to but spaced from the side wall of said loop-taker body-member, and a flexible wiper-element extending from the inner face of said side wall of the loop-taker body-member in a direction oppositely to said beak and circumferentially of the

outer face of said side wall of the thread-carrier member said wiper-element comprising a doubled strip of flexible material and having the doubled end thereof in proximity to said outer face of the thread-carrier member.

13. A rotary loop-taker for sewing machines, having a body provided with a needle-thread-loop seizing beak, a thread-carrier associated with said loop-taker and provided in a wall thereof with a needle-clearance opening, and means carried by said loop-taker for maintaining said wall in the region of said needle-clearance opening substantially free from an accumulation of foreign matter.

14. In a sewing machine rotary loop-taker having a body provided with a needle-thread-loop seizing beak, and a thread-carrier associated therewith, and formed with a needle-clearance opening, the improvement which consists in the provision on said loop-taker body of a wiper having a path of movement in proximity to said opening.

15. A rotary loop-taker for sewing machines, including a cup-shaped body-member having a

cylindrical side wall, said side wall being provided with a needle-thread-loop seizing beak and with a slot extending inwardly from the rim of said side wall, a thread-carrier associated with

5 said loop-taker and having a wall thereof proximate to but spaced from said side wall of the loop-taker, a wiper-element disposed in said slot and extending therefrom into wiping relation to said wall of the thread-carrier, and means for 10 securing said wiper-element for rotation with said loop-taker.

16. A rotary loop-taker for sewing machines, including a cup-shaped body-member having a cylindrical side wall, said side wall being provided with a needle-thread-loop seizing beak and with a slot, a thread-carrier member associated with said body-member and having a wall thereof proximate to but spaced from said side wall, a wiper-element extending through said slot and 15 between the walls of said members, and a plate 20 detachably secured upon said body member of the loop-taker in wiper-element clamping position.

JAMES E. WERTZ.
